UNITED STATES PATENT OFFICE.

EDWARD F. HOTCHKISS, OF THOMASTON, CONNECTICUT.

DESIGN FOR A WALL-HOOK.

SPECIFICATION forming part of Design No. 13,698, dated March 6, 1883.

Application filed December 26, 1882. Term of patent 7 years.

To all whom it may concern:

Be it known that I, EDWARD F. HOTCHKISS, of Thomaston, in the county of Litchfield and State of Connecticut, have invented 5 a new and Improved Design for Wall-Hooks, of which the following is a full, clear, and exact description.

Reference is to be had to the accompanying drawings, forming a part of this specification, 10 in which similar letters of reference indicate corresponding parts in both the figures.

Figure 1 is a perspective view of my newly-designed wall-hook. Fig. 2 shows a modification of the shank-recess.

15 Heretofore wall-hooks have been made with the receiving recesses or bends close to the base of the hooks.

The leading feature of my design consists in the arched base and the horizontally-projecting shanks having recesses at their outer ends.

20 The base A of the hooks is arched between the shanks B, and the said shanks B project

horizontally and have recesses C in the upper sides of their outer ends.

By this design a pleasing and attractive 25 form is given to the wall-hooks, calculated to attract purchasers.

Having thus described my invention, I claim as new and desire to secure by Letters Patent—

1. The design for wall-hooks herein shown 30 and described, the same consisting of the arched base A and the horizontally-projecting shank B, having recesses C in the upper sides of their outer ends.

2. The design for wall-hooks herein shown 35 and described, the same consisting of the arched base A.

EDWARD F. HOTCHKISS.
